THREAD GUIDE BRAKE

Woldemar Heinitz, Chemnitz, Germany, assignor
to Schubert & Salzer Maschinenfabrik Aktien-
gesellschaft, Chemnitz, Germany

Application January 23, 1935, Serial No. 3,164
In Germany February 6, 1934

2 Claims. (Cl. 66—126)

The present invention relates to flat knitting machines and more particularly to the thread guide brakes of such machines.

It is already well known to provide two thread guide brakes for the thread guide rod to prevent rebound of this rod even at higher speeds.

The arrangement of two thread guide brakes, however, allows a relatively small increase of the speed only.

10 According to the present invention, however, the speed during narrowing may nearly be increased to the normal speed the machine has during the manufacture of plain rows of loops.

With this object in view, the present invention consists in providing two thread guide brakes for each direction of the sinking movement, said thread guide brakes operating one after the other in such a manner, that the thread guide rod is held against the stop first by the action 15 of the one brake and then by the additional braking action of the second thread guide brake.

In the accompanying drawing, forming part of the specification, the invention is shown by way of example.

25 In the drawing:

Fig. 1 is a front elevation of one construction of brake arrangement according to the invention.

Fig. 2 shows a view, similar to Fig. 1, of a modified construction of the invention and

Fig. 3 is a broken away front elevation of a further modified brake arrangement in accordance with the invention.

Referring now to the example shown in Figure 35 1, the connecting rod 1 is reciprocated in the usual manner by means not shown in the drawing and carries bearings 2 in which a brake rod 3 is mounted. On the brake rod 3 are mounted the thread guide brakes 4 and 5. In bearings 6, 40 also carried by the connecting rod 1, a brake rod 7 is journaled on which the thread guide brakes 8 and 9 are mounted. Stops 4' and 5' provided at the thread guide brakes 4 and 5 respectively are adapted to act upon an intermediate member 10 engaging a fork 11 forming part of a sleeve 11' on the thread guide rod 12. Stops 8' and 9' provided at the thread guide brakes 8 and 9 respectively are adapted to act upon an intermediate member 13 the free end of which engages 45 a fork 14 forming part of a sleeve 14' on the thread guide rod 12. The arrangement is such, that the free end of the member 10 exactly fits the fork 11 of the sleeve 11', while the free end of the member 13 engages the fork 14 of the 50 sleeve 14' with some play. The movements of

the thread guide bar 12 are limited by fixed stops 15 and 16.

During movement of the connecting rod 1 in the direction of the arrow A in Fig. 1, the thread guide rod 12 is shifted by the intermediate member 10 actuated by the thread guide brake 5. The intermediate member 13 during this shifting movement bears against the right hand prong of the fork 14 of sleeve 14'. If the thread guide rod 12 comes into contact with the fixed stop 10 15 16, the intermediate member 13 is, during the continued movement of the connecting rod 1, shifted further by the thread guide brake 9 until it bears against the left hand prong of the fork 14 of the sleeve 14'.

The thread guide rod 12, therefore, is held against the fixed stop 16 first by the thread guide brake 5 and later on also by the thread guide brake 9.

During movement of the connecting rod in 20 the direction of the arrow B in Figure 1, the thread guide rod 12 is shifted by the brake 4 acting upon the intermediate member 10. The intermediate member 13 during this movement bears against the left hand prong of the fork 14 25 of the sleeve 14'. If the thread guide rod 12 comes into contact with the fixed stop 16, the intermediate member 13 is, during the continued movement of the connecting rod 1, shifted further by the thread guide brake 8 until it bears 30 against the right hand prong of the fork 14 of the sleeve 14'.

Hereby, as described with reference to the movement of the thread guide rod 12 in the direction of the arrow A, the rod 12 also is held 35 against the fixed stop 16 first by the thread guide brake 4 and later on by the thread guide brake 8 also.

According to the modification shown in Fig. 2, the thread guide brakes 4 and 5 are provided with 40 stops or lugs 17 and 18 respectively, while the thread guide brakes 8 and 9 are provided with stops or lugs 19 and 20 respectively. The distance between the lugs 17 and 18 is a little smaller than the distance between the lugs 19 and 20. 45 Mounted on the thread guide rod 12 are sleeves 21, 22 each having a nose 21', 22' respectively.

The stop or lug 18 is adapted to act upon the nose 21' during the movement of the thread guide rod 12 in the direction of the arrow A. By 50 reason of the particular arrangement described above, a clearance still exists between the stop or lug 20 and the nose 22' of the sleeve 22. As soon as the thread guide rod 12 comes into contact with the fixed stop 16, the stop or lug 20, on 55

further movement of the connecting rod 1, engages the nose 22', so that the thread guide rod 12 is held against the fixed stop 15 by the two stops or lugs 18 and 20. On movement of the 5 thread guide rod 12 in the opposite direction, i. e. in the direction of the arrow B, towards the fixed stop 16, the action of the brake arrangement is the same. First the lug 17 acts on the nose 21. of the sleeve 21 at which time a clearance still 10 exists between the lug 19 and the nose 22' of the sleeve 22. When, however, the thread guide rod 12 comes into contact with the fixed stop 16, the lug 19 engages, during further movement of the connecting rod 1, the nose 22' of the sleeve 22, so 15 that now the thread guide rod 12 is held against the fixed stop 16 by means of both lugs 17 and 19. In Fig. 3 a modification is shown according to 20 which the two thread guide brakes 4 and 5 are arranged directly one behind the other in the longitudinal direction of each brake rod and carry a lug 10 engaging a fork 11 provided on the thread guide rod 12. The jaws 25 and 26 of the brakes are, in a well known manner, actuated by springs 27 and 28 respectively. The jaws 26 of the brake 25 are a little shorter than the width of the bearing, while the corresponding spring 28 fits the bearing without play. The brake jaws 26, therefore, may slide upon the brake rod 3 and in each 30 direction of movement of the thread guide rod 12 they come into action as soon as the thread guide rod engages the fixed stop. That is to say, during movement of the thread guide rod 12 in the direction of the arrow B, first the thread guide 35 brake 4 and then the thread guide brake 5 comes into action, whereupon on movement in the direction of the arrow A also first the thread guide brake 4 and then the thread guide brake 5 comes

into action, as the brake jaws of the latter had been shifted in their bearing.

The thread guide brake according to the invention may be used in connection with any kind of thread guide rods, i. e., for thread guide rods adapted for the manufacture of plain work 5 as well as for thread guide rods adapted for making plated work.

Of course, the same effect is obtained, if the brakes are arranged side by side in a brake casing 10 instead, as shown in Fig. 3, directly one behind the other.

What I claim is:

1. In a thread guide brake mechanism for flat knitting machines, a thread guide rod, a brake rod, a brake housing carried by said brake rod, a brake lug carried by said brake rod and subdividing said housing in two halves, a sleeve on said thread guide rod, a fork formed at said sleeve and adapted to receive the free end of said brake lug, a pair of brake jaws exactly fitting one half of said brake housing, a spring co-operating with said brake jaws exactly fitting said one half of said brake housing, a second pair of jaws arranged with play in the other half of said brake housing, and a second spring co-operating with said second pair of brake jaws and exactly fitting said other half of said brake 20 housing.

2. In a thread guide brake mechanism for flat knitting machines, a thread guide rod, fixed stops limiting the reciprocating movements of said thread guide rod, a brake housing, and two brake members arranged in said brake housing and acting successively on said brake guide rod toward 30 the end of its movement in either direction as limited by said fixed stops.

WOLDEMAR HEINITZ.
